Patented Dec. 21, 1915.

UNITED STATES PATENT OFFICE.

HOPE LATHAM, OF NEW YORK, N. Y.

REFRIGERATOR.

1,165,185.

Specification of Letters Patent. Patented Dec. 21, 1915.

Application filed May 4, 1911. Serial No. 625,011.

To all whom it may concern:

Be it known that I, HOPE LATHAM, a citizen of the United States, and a resident of New York city, in the county of New York and State of New York, have invented certain new and useful Improvements in Refrigerators, of which the following is a specification.

This invention relates to improvements in refrigerators and, in particular, to domestic household refrigerators, and has for its object the construction of a simple, efficient and very cheap apparatus which at the same time will be economical in the use of ice.

15 Figure 1 is a horizontal section of the apparatus along the line A—B of Fig. 2. Fig. 2 is a vertical cross-section of same along the line C—D of Fig. 1, and Fig. 3 is likewise a vertical cross-section of the refrigerator taken at right angles to Fig. 2 along the line E—E of Fig. 1.

In brief, my invention consists of a refrigerator having an ice compartment in the upper part thereof, said compartment being 25 arranged to permit free circulation of air through its bottom to the storage compartment below, air circulating channels disposed along the sides of said refrigerator establishing communication between the 30 upper portion of the ice compartment and the lower portion of the storage compartment, and regulating dampers disposed in said air circulating channels.

My invention will be more clearly understood by the following detailed description.

35 1 is the outside casing, preferably made of some suitable and inexpensive material such as wood pulp or papier mâché, 2 is the ice compartment and 3 the provision storage 40 compartment.

45 4 and 5 are the air circulating channels communicating with the lower portion of the provision storage compartment respectively through the openings 6 and 7 formed by the spaces left between the lower edges of the sheet metal sides 8 and 9 respectively and the bottom sheet 10. The upper edges of the sides 8 and 9 do not extend to the top of the refrigerator, but terminate a 50 short distance from said top so as to form the spaces 11 and 12 establishing communication between the upper portion of the ice compartment and the air circulating channels 4 and 5 respectively.

55 13 and 14 are dead air spaces formed between the casing 1 and the sheets 15 and 16

respectively, which sheets extend the entire length of the refrigerator from the lower bottom sheet 10 to the top of the outside casing of the same, thus preventing the circulation of air therethrough. The dead air space 14 has a properly walled passage 17 therethrough for the introduction and withdrawal of provisions or other substances to be preserved in the storage compartment of 65 said refrigerator. In order to prevent any fresh air from entering the space 14 through the opening 17, a horizontal sheet 18 is disposed therein, as well as the two vertical sheets 19 and 20.

70 21 is the door giving access to the storage compartment and has attached to its inner side the air box 22, and is arranged to have as small a clearance as possible with the horizontal sheets 18 and 10 and vertical 75 sheets 19 and 20, and to fulfil this purpose the vertical sheet 20 in the dead air space 14, as well as the edge 23 of the box 22 of the door 21, are shown made parts of arcs of concentric circles with the pivot 24 of the 80 door as the center of their radii.

25 are a series of inverted V-shaped members extending across the lower part of the ice compartment forming a bottom to support the ice, said members being spaced 85 apart from each other, thus allowing for the free circulation of the air through the spaces between said V-shaped members, and are supported by the transverse members 26 and 27, fastened respectively to the sides 16 and 15 90 in any suitable manner.

28 are inclined V-shaped troughs, also having spaces left between them and so disposed in relation to the inverted V-shaped ice-supporting members that the water 95 formed by the melting ice resting on said members 25 drips into 28, and, due to their slight inclination, the liquid flows to the lower ends of said troughs 28. Small tubes 29 are attached to each of said troughs 28 100 through which the water flows and is collected in the transverse trough 30. To one end of this transverse trough 30 is attached the drain pipe 31, which contains some suitable means, 32, at its lower end to prevent 105 the entrance of air therethrough.

33 is a catch basin for collecting the water discharging from the drain pipe 31.

34 and 35 are cross members supporting the ends of the V-shaped troughs 28 and are 110 attached in some suitable way to the sheets 16 and 15 respectively.

36 and 37 are dampers placed in the air circulating channels to regulate the current of air passing therethrough, and thus the rate of circulation may be regulated.

5 38 is the lid covering the opening through which the ice is placed in the compartment 2.

39 is a rubber gasket attached to the lid 38, making the lid 38 air-tight. A similar gasket, 40, is attached to the door 21.

10 42 is a compression latch forcing the rubber gasket tightly against the casing 1 when the door 21 is closed.

43 is a dead air space, and may be filled with some heat insulating material such as

15 sawdust.

Shelves, 44 and 45, are placed in the compartment 3, and are preferably arranged so that the cold air may circulate through them.

Any such arrangement will suffice, the one 20 shown being simply metal rods or thin slats spaced apart and joined together at their ends where they are supported by the members 46.

41 are springs designed to hold the butterfly dampers 36 and 37, in any desired position.

The operation of the apparatus is evident from the drawings. The cold air circulation is shown by the arrows. The water formed 30 by the melting ice drips down the inclined sides of the members forming the ice compartment bottom and through the spaces left between them, into the inverted inclined V-shaped troughs 28, and flows down this plurality of troughs to their lower ends, through the several tubulations 29 to the transverse trough 30, where all the currents of water flowing through the troughs 28 are united 35 into one stream which is carried out of the refrigerator by the drain pipe 31 and delivered to the catch basin 33.

It is to be distinctly understood that I do not limit my invention to the exact details of construction shown, as it is evident that 45 many details may be changed without in any way departing from the main characteristic features of the invention. As an example, I have shown my preferred form of outside casing to be circular in horizontal cross-section. It may, however, be made, where preferred, of any curved cross-section, it being 50 advantageous however to have the construction follow the general arrangement shown, in which the inscribed rectangular ice and 55 storage compartments make a tight joint with the inclosing outer shell and are directly attached thereto. Such a construction insures greater structural rigidity as well as greater cheapness of construction 60 than other types shown in the art—such for instance, as the construction in which the inner compartment is also circular in cross-section and attached to and spaced from the outer shell by separate spacing 65 members. By thus combining rectangular

ice and storage compartments with an outer cylindrical shell I secure the construction that affords the greatest convenience with the greatest rigidity of structure and the least heat-radiating surface.

70 It is evident that by adopting some such ice-supporting-bottom as is herein described that the shortest possible path is obtained for the cold air in going from the ice compartment to the storage compartment so that the air practically reaches the upper portion of the storage compartment at the same temperature that it has in the ice compartment. The return passages for the air, from the storage compartment to a point in the ice compartment a little above the upper surface of the ice therein, are also as direct as possible.

75 Another advantageous feature of my invention is the insertion of dampers in the air circulating channels or passages. It is evident that the faster the circulation of air through the apparatus, the cooler will be the storage compartment, due to the increased rate of heat transference from the 80 storage compartment to the ice, and the consequent increase in the rate of melting of the latter. Now, if there should be no provisions to be preserved in the storage compartment there would be no object in maintaining that compartment cold, by having a circulation of air therethrough with a waste 85 of ice, and in such a case the dampers in the circulating channels are closed, thus preventing any circulation therethrough with a 90 consequent saving of ice. This feature of preserving the ice is a very important one as it reduces the expense of ice to a considerable amount.

95 The advantages gained by my invention 100 are not obtained at the expense of elaborate and expensive construction but, on the contrary, by the simplest possible construction and the use of very inexpensive materials.

Having thus described my invention, I 110 desire to secure by Letters Patent and claim the following:

1. In a refrigerator of circular horizontal cross-section, an inscribed rectangular chamber, two of the sides of said rectangular chamber extending from the bottom to the top of said refrigerator to form two dead air spaces, the top edges of the other two sides of said rectangular chamber terminating a short distance below the top of said 115 refrigerator, and the lower edges of both of the said two sides terminating a short distance above the bottom of said refrigerator, forming thereby air circulating channels between said sides of said rectangular chamber and the outside circular casing of said refrigerator, an ice compartment in the upper part of said rectangular chamber, a storage compartment in the lower part of said rectangular chamber, means for supporting 120

the ice in said compartment, means adapted to intercept water from dropping into said storage compartment but to allow the free circulation of air thereto, and regulating 5 dampers in said air circulating channels, substantially as described.

2. In a cylindrical refrigerator, the combination of an inscribed rectangular chamber, two opposite sides of said rectangular 10 chamber extending from the bottom to the top of said refrigerator, forming two dead air spaces with the outside cylindrical casting, the top edges of the other two opposite sides terminating a short distance below the 15 top and their lower edges above the bottom of said refrigerator, thereby forming two air circulating channels communicating with said inner rectangular chamber at the top and bottom thereof, an ice supporting means 20 transversely disposed in the upper portion of said inscribed chamber, a drip-intercepting means transversely disposed in said chamber immediately below said ice-supporting means, both said ice-supporting and 25 said drip-intercepting means being constructed to permit of the free flow of air therethrough, whereby said inscribed chamber is adapted to form the down-cast channel for the cooling air, dampers for regulating 30 the circulation through said air-circulating channels, a door-way inserted in one of said dead air-spaces, a heat-insulated door closing said door-way and a top-closure for said refrigerator.

3. As an article of manufacture, a refrigerator having a substantially cylindrical outer shell, a rectangular ice compartment in the upper part of said refrigerator, the walls of said ice compartment extending 40 downward to form the walls of the storage compartment, two dead air spaces formed between two opposite walls of said ice and

storage compartments and said outside cylindrical shell, two air circulating channels formed between the other two opposite walls 45 of said ice and storage compartments and said outside cylindrical shell, said air circulating channels communicating with said ice compartment at their tops and communicating with the storage compartment at their bottoms, said ice and storage compartments together forming the downcast passage for the cooling air, while said air circulating channels constitute the upcast passages for the cooling air, and regulating dampers located in said air upcasts, substantially as described.

4. As an article of manufacture, a refrigerator having an outer shell of curved horizontal cross-section, an approximately rectangular chamber inscribed within said outer shell in such manner as to form upcast channels for air between two opposite walls of said chamber and said outer shell, dead air-spaces between the other two opposite walls and said outer shell, the so-formed up-cast channels communicating with said inscribed chamber at the top and bottom thereof, ice-supporting and drip-intercepting means located in the upper portion of 70 said inscribed chamber, whereby said upper portion is adapted to contain ice, said ice-supporting means being constructed to permit the free flow of air therethrough, whereby said inscribed chamber is adapted to form 75 the down-cast passage for the cooling air.

Signed at New York city in the county of New York and State of New York this 2nd day of May A. D. 1911.

HOPE LATHAM.
